UNITED STATES PATENT OFFICE.

WILLIAM A. HOLMAN, OF PHILADELPHIA, PENNSYLVANIA.

DESIGN FOR A MOUNTING FOR BOOK-COVERS, &c.

SPECIFICATION forming part of Design No. 27,520, dated August 17, 1897.

Application filed May 13, 1897. Serial No. 636,399. Term of patent 7 years.

To all whom it may concern:

Be it known that I, WILLIAM A. HOLMAN, a citizen of the United States, residing in the city of Philadelphia, State of Pennsylvania, 5 have invented a certain new and original Design for the Ornamentation of Book-Covers, of which the following is a full, clear, and exact description, reference being had to the accompanying drawings, forming a part of this 10 specification.

My invention relates to the ornamentation of book and album covers; and it consists in the novel form or configuration of a mounting to be applied to such exterior covers, 15 substantially as shown in the accompanying drawings, in which—

Figure 1 shows one of the mountings applied to a plush album-cover, a mirror, for illustration, being shown as held in place on 20 the cover of the book within or beneath the inwardly-projecting or flanged edges of the open center of the mounting. Fig. 2 is a section on the line *a b* of Fig. 1, showing the form or configuration of the open center of the mounting and its relation to the mirror or other ornamental device held down thereby on the 25 book-cover.

The design consists more particularly in the general outline shape of the mounting, the

form of which is the general shape of an open 30 fan with a central open portion or panel. The inner edge of said mounting is flanged, the flanges projecting inwardly and slightly upward in a plane above the exterior portions that rest on the book-cover, in order that the 35 beveled edges of the mirror or other ornamental device to be held on the book-cover may be maintained in position beneath such flanges and within the open center of the mounting.

Referring to the drawings, A represents the 40 inwardly-projecting and slightly-upturned flanges, B the flat portion resting against the book-cover, and C the bevel-edged mirror or other ornament held in place thereby on the book-cover.

What I claim as new and of my invention 45 is—

A design for a mounting for a book or album cover, substantially as herein shown and described.

In testimony whereof I have hereunto affixed my signature this 10th day of May, A. D. 50 1897.

WILLIAM A. HOLMAN.
